Attorney

UNITED STATES PATENT OFFICE.

OTIS T. CRAFTS, OF MANCHESTER, NEW HAMPSHIRE, ASSIGNOR TO CRAFTS PROCESS, INC., OF MANCHESTER, NEW HAMPSHIRE, A CORPORATION OF MAINE.

PROCESS OF MAKING HORSESHOE RANDS.

Application filed January 28, 1927. Serial No. 164,208.

The present invention relates to rands, and more particularly to rands of the horseshoe type, adapted for use in the manufacture of boots and shoes.

- 5 An important object of the present invention is the provision of a horseshoe rand which will be extremely economical to manufacture, and which will have all of the advantages of present commercial horseshoe 10 rands. The present horseshoe rand is manufactured, died out, or cut from very expensive heavy leather stock, this having been considered the only feasible way in which such a horseshoe rand could be produced.
- 15 However, I have discovered that a horseshoe rand can be constructed from the cheapest of leather materials, such as scrap leather, pieces of leather which have heretofore been considered waste, skivings, or in 20 fact practically any form of inexpensive leather pieces or scraps may be utilized in carrying out my present invention.

Fundamentally considered, the present invention consists in utilizing a plurality of 25 pieces of scrap or waste leather, assembling these pieces in rough form, dieing same out to a true horseshoe shape, and then gouging or bevelling in said assembled sections a suitable concavity for application to the heel 30 seat of a shoe. I also contemplate, if necessary, skiving or levelling said assembled sections to the proper finished height of the outside edge, in the event that such assembled portions or sections should be higher 35 than required.

In my prior and co-pending application, Serial No. 56,112, filed September 14, 1925, I have illustrated one method of forming a heel base with a rand-like rim cut directly 40 in said base, instead of utilizing a separate rand structure. The surface of the blank into which the rand-like rim is formed as described in said co-pending application, is preferably comprised of two half sections, 45 meeting at a line substantially central of the rear portion of the base. When subjected to the gouging or cutting action, to form the rand-like rim in the base, a part of these half lifts or pieces is cut or severed from the 50 base. Such parts have heretofore been considered as waste, and therefore, as a total loss. I have discovered, however, that these severed pieces are ideally adapted for the manufac-

ture of a horseshoe rand as described in the present application. Due to the cutting action of the gouging or bevelling machine, in forming the heel base of my said prior application, portions of the severed pieces are already bevelled, and lend themselves with peculiar adaptability to being assembled and secured together for the subsequent dieing therefrom of a horseshoe rand blank. These pieces are assembled for such purpose without any further cutting or forming operation. Subsequent to being died in the horseshoe rand blank shape, if such blank is of a height greater than that required for the finished edge height of the rand, I may subject said blank to a levelling or skiving operation to reduce said blank to the desired 60 height. Subsequent to the levelling operation, if same is required, I then subject the blank to a further cutting operation, which cutting operation is designed to gouge or cut a suitable concavity within the confines of 65 the edge of the rand to adapt the rand for ready and even fitting to the heel seat of a shoe. In its completed form and when applied to the shoe, such a rand is undistinguishable from a rand manufactured from 70 expensive heavy leather stock, the overlapping edges of the united sections or pieces forming the rand being substantially unnoticeable in the completed article.

I believe that such a horseshoe rand, comprised of a plurality of overlapping sections, and constructed from material of little or no value, and yet resulting in a rand of equal qualifications with the expensive horseshoe rand heretofore produced, is novel, and 80 I therefore claim the same herein broadly.

Further features of the invention, novel combinations of parts, and advantages, will be hereinafter more fully pointed out and claimed.

Referring to the drawings, illustrating a preferred embodiment of the invention—

Fig. 1 illustrates a heel base, in which a rand-like rim has been formed;

Fig. 2 is a perspective view of the portion 100 severed during the forming of the rand-like rim in the base of Fig. 1;

Fig. 3 is a perspective of three of these half pieces united together in rough form;

Fig. 4 is a perspective of the horseshoe 105 rand blank died from the structure of Fig. 3;

Fig. 5 is a side elevation illustrating the reduction of the blank of Fig. 4 to desired height; and

Fig. 6 is a perspective of the completed 5 horseshoe rand.

While I have illustrated herein the pieces or sections to be utilized in the formation of my novel horseshoe rand as being thus severed from the heel base of my said co-pending application, Serial No. 56,112, it will be appreciated that I am not limited thereto, but may utilize any pieces of scrap, waste or inexpensive leather stock which can be assembled in the relative formation as illustrated in Fig. 3. However, I find that these half pieces severed from the base of my said co-pending application are peculiarly well adapted for the purpose herein described, and I have therefore illustrated the rand of 10 the present application as constructed therefrom.

As shown in the drawings, the base 1 is composed of a plurality of layers 2, 3 and 4. In the layer 3 has been formed a suitable 25 heel seat concavity, with a rand-like rim around the edge thereof. In Fig. 2, at 5, is illustrated generally the piece or section severed from the base 1 during the process of manufacture. This section 5 comprises 30 two strips or pieces 6, roughly formed in equal halves. I separate these strips 6, and assemble any desired number of same, in the form shown in Fig. 3. As shown in Fig. 3, I have utilized three of these strips 6, and 35 have assembled same with the flesh side up, the flesh side being the side with the bevelled surface thereon.

As shown in Fig. 3, the three strips 6 are united at 7, 7 the bevelled surfaces co-operating to form a fairly even top and bottom surface to the structure of Fig. 3. The strips 6 are preferably glued, cemented or otherwise secured at the contacting portions 7.

After being thus assembled, as illustrated 45 in Fig. 3, the rough blank is then subjected to a dieing operation, as a result of which the horseshoe rand blank 8 is formed. This blank 8 in Fig. 4, illustrates very clearly 50 the line of jointure of the bevelled surfaces 7, and the evenness with which such a blank is formed from the rough structure of Fig. 3.

In the event that the blank 8 is higher than required for the completed heel base

I may subject same to a skiving or levelling 55 operation, removing therefrom the surplus of material not required, here designated generally as the strip 9. When reduced to the proper and desired finished height, the blank 8 is then subjected to a cutting or 60 gouging operation, producing a suitable and desirable concavity within the outer rim of the blank, and resulting in the completed rand 10 illustrated in perspective in Fig. 6.

Thus it will be seen that I have produced 65 a true horseshoe rand from inexpensive and otherwise waste material. The rand illustrated and described herein is applicable in all places where prior expensive horseshoe rands could be utilized, on the most expensive shoes, and will stand up, in use, equally 70 as well as the prior horseshoe rands. The rand of the present invention will also take the edge finishing and burnishing, inking, and other finishing operations, equally as 75 well and thoroughly as prior rands.

While I have necessarily described my present invention somewhat in detail, it will be appreciated that I am not limited to the specific form of pieces utilized to form my 80 present rand, but may vary the size and shape of these pieces, as well as the size and shape of my novel rand, within wide limits without departing from the spirit of the 85 invention.

My invention is further described and defined in the form of a claim as follows:

That improvement in the art of producing leather rands for use in the manufacture 90 of boot and shoe heels, which consists in assembling a plurality of waste leather sections of varying thickness, each section formed from wedge-like waste material, utilizing such sections with the thicker edge 95 of the wedge-like portion positioned in the outermost edge of the finished rand, overlapping and securing the wedge-like sections together by adhesive independent of separate scarfing or beveling actions on the contacting surfaces of said sections, applying 100 pressure thereto, dieing out the united sections into desired horseshoe form, and thereupon subjecting the blank to a cutting action 105 to form a rand-like rim.

In testimony whereof, I have signed my 110 name to this specification.

OTIS T. CRAFTS.
